UNITED STATES PATENT OFFICE.

CHARLES H. LEATHERMAN, OF CLEVELAND, OHIO, ASSIGNOR TO THE PIONEER MANUFACTURING COMPANY, OF CLEVELAND, OHIO, A CORPORATION OF OHIO.

DUSTER.

1,416,480.

Specification of Letters Patent. Patented May 16, 1922.

Application filed January 18, 1918. Serial No. 212,519,

To all whom it may concern:

Be it known that I, CHARLES H. LEATHERMAN, a citizen of the United States, residing at Cleveland, in the county of Cuyahoga and State of Ohio, have invented a certain new and useful Improvement in Dusters, of which the following is a full, clear, and exact description.

The present invention relates to an article 10 useful as a dust removing and absorbing device, which is so constructed as to protect the hand of the user from contamination by dust or dirt, and further, the article is so constructed as to enable the hand of the user 15 to manipulate a thick mass of long strands of yarn-like material in contact with the article or object from which dust is to be removed.

The invention further consists in a method 20 of manufacture in accordance with which method the article may be conveniently produced at low cost.

Generally speaking, the invention comprises the combination of elements forming 25 the article and the steps in the method hereinafter more fully set forth in the claims.

Reference should be had to the accompanying drawings forming a part of this specification, in which Fig. 1 is a top plan 30 view of the duster; Fig. 2 is a bottom plan view of the duster; Fig. 3 is an end elevation; Fig. 4 is a fragmentary view showing a detail of construction; Fig. 5 is a fragmentary view showing a detail of construction; Fig. 6 is a plan view showing the manner in which the strands of yarn are sewed; 35 and Fig. 7 shows a step in the method of manufacturing the article.—

In making up the article of this invention, 40 the construction provides an envelope or mitten which is adapted to receive the hand of a user. This envelope comprises a palm side 1, which is so designated because the palm of the hand of the operator contacts 45 with it, and also includes a back side of the mitten indicated at 2. These two sides of the mitten are formed of such a size as to make a convenient container for the hand of the user, and the edges of the sides are 50 sewed to each other all around, except at one end, where the sides are not sewed, thereby providing an opening through which the hand of the user may be inserted.

The seam formed by the sewing of the

edges of the parts 1 and 2 of the envelope 55 or mitten is indicated at 3.

Upon the palm side 1 there are secured a plurality of rows of long strands of yarn-like material, these rows being indicated at 4 and 5. Similarly there is a row of strands 60 of yarn which are secured at the edge of the mitten, preferably to the seam 3 by which the parts of the envelope are joined. This row of yarn is indicated at 6.

The rows or strips of yarn-like material 65 are secured to the mitten in such position relative to each other that when they are sewed to the envelope, there is formed a mass of long strands of yarn-like or fibrous material which thickly hangs and in effect 70 forms a mop-like construction. When the hand of the user is inserted in the envelope or mitten the mass of yarn strands may be moved and manipulated by the hand and fingers of the user in a free manner which permits 75 the yarn strands to be conveniently brought into contact with the article to which it is applied, for the purpose of removing the dust or dirt. The flexibility of structure permits the yarn to be worked by the hand 80 of the user into the crevices and around projections which may be upon the article to be dusted. Thus the structure provides all the pliability and flexibility of a cloth duster, but has the further advantage that the hand 85 of the user is self-protected from becoming grimed or encrusted with dirt, and has the further advantage that the duster is at all times, as it were, secured to the hand of the user so that no annoyance or inconvenience 90 is experienced by dropping or otherwise losing control of the duster.

Another decided advantage lies in the fact that the long strands of yarn as they are moved and manipulated over the surface to 95 be dusted are continuously changing their relationship to each other and exposing new surfaces of the yarn that may come in contact with the article to be dusted, thereby forming an efficient dust removing device.

From the foregoing description it will be seen that the device described in effect forms a hand mop in which the hand of the user is protected and at the same time the mop is caused to, as it were, be attached to the hand 105 of the user, thereby enabling its easy and convenient manipulation.

In practice it is preferable that the strands

of yarn be impregnated with a suitable dust absorbing oil. This feature, however, is not claimed as any part of the invention, inasmuch as I am aware that this is common 5 practice in the preparation of floor mops.

In manufacturing such an article as has been described, it will at once be appreciated that the cost of manufacture must be kept low, and furthermore, it is important that 10 the method employed in the manufacture shall be such as to enable a large production, at the same time to produce the article in such form that it is of neat appearance so as to commend itself to the purchasing 15 public.

In proceeding with the manufacture of the device, the sides 1 and 2 are cut from cloth of suitable texture, and the edges are sewed to each other, forming the seam which is indicated at 3, except that in the first step of 20 the manufacture the seam when sewed is upon the outside of the envelope. The envelope is then turned inside out so that the raw seam 3 is upon the inside of the envelope. 25

Next the palm side or side 1 is given a longitudinal fold such as indicated at 7 in Fig. 7. This is a flat fold, that is to say, the material is folded back upon itself. A strip 30 of long strands of yarn which are arranged with respect to each other as indicated in Fig. 6 is laid upon the folded cloth so that substantially the center of the strands of yarn is adjacent the edge of the folded piece 35 of material. In this position a row of stitches made by a sewing machine is passed through the yarn and the folded material in such fashion that the strands of yarn are sewed to the folded material and are thereby 40 firmly secured thereto. Other longitudinal strips of yarn material may be secured to the palm side of the envelope in the same manner as that which has been indicated.

It will be seen that by this method the 45 yarn is secured to the envelope and may be sewed thereto by the use of ordinary sewing machines, and that when the sewing is completed the yarn will be firmly held to the seam which has been formed, thus producing 50 a strong construction.

However, the strength of the construction produced is not the essential feature, but is incident to the method of manufacture.

Obviously, as many longitudinal rows or 55 strips of yarn may be sewed to the palm side of the envelope as may be deemed necessary.

It will be apparent that by the sewing of

the two parts of the envelope or mitten to each other, the seam 3 has been formed as heretofore described. Therefore, in attaching the strip of yarn to this seam, the mitten is placed in such position that the seam is laid flat and then the strip of strands of yarn is laid upon this seam in such fashion that the middle of the strands is in contact with the seam. In this position the yarn is sewed to the seam by a sewing machine and thus becomes firmly attached. The strands of yarn are of such length that when the envelope is inverted so that the palm side is 70 down, which is the position in which the duster is ordinarily used, the strands of yarn hang substantially equally on both sides of the point at which they are secured, and the various strands of yarn fall toward each 75 other and intermingle to form a mass of yarn strands.

After considerable experimentation it was found that the foregoing method was the practical method for expeditiously manufacturing these dusters at a low cost. 80

The obvious method would be to sew the longitudinal strands of yarn directly to the palm side of the duster, and subsequently sew the back of the duster to the palm side, 85 but this would leave a raw edge at the portion where the back and palm side of the mitten or envelope were sewed to each other, which would make an article of unpleasing appearance, and not so salable as the one 90 proposed.

Having described my invention, I claim.

1. An article of manufacture comprising an envelope adapted to receive a hand of the user, said envelope having a back and a palm 95 side, said sides being secured at their edges by sewing to form a seam, a row of thickly hung strands of yarn sewed to the said seam at the edge of the envelope, a plurality of folds extending upon the palm side of the 100 envelope, and a row of thickly hung strands of yarn secured to each of the said folds on the palm side of the envelope, said rows of yarn constituting a mass having a substantially continuous outer surface. 105

2. An article of manufacture comprising an envelope adapted to receive the hand of the user, said envelope being provided on the palm side between the edges thereof with folds and a row of thickly hung strands of 110 yarn secured to each of said folds.

In testimony whereof, I hereunto affix my signature.

CHARLES H. LEATHERMAN.
